(57) **CLAIM**

The ornamental design for a headphone stand as shown and described.

DESCRIPTION

FIG. 1 is a rear perspective view of a first embodiment of a headphone stand.

FIG. 2 is a left elevation view thereof.

FIG. 3 is a right elevation view thereof.

FIG. 4 is a rear elevation view thereof.

FIG. 5 is a front elevation view thereof.

FIG. 6 is a top plan view thereof.

FIG. 7 is a bottom plan view thereof.

FIG. 8 is a rear perspective view of a second embodiment of a headphone stand.

FIG. 9 is a left elevation view thereof.

FIG. 10 is a right elevation view thereof.

FIG. 11 is a rear elevation view thereof.

FIG. 12 is a front elevation view thereof.

FIG. 13 is a top plan view thereof.

FIG. 14 is a bottom plan view thereof.

FIG. 15 is a rear perspective view of a third embodiment of a headphone stand.

FIG. 16 is a left elevation view thereof.

FIG. 17 is a right elevation view thereof.

FIG. 18 is a rear elevation view thereof.

FIG. 19 is a front elevation view thereof.

FIG. 20 is a top plan view thereof.

FIG. 21 is a bottom plan view thereof.

FIG. 22 is a rear perspective view of a fourth embodiment of a headphone stand.

FIG. 23 is a left elevation view thereof.

FIG. 24 is a right elevation view thereof.

FIG. 25 is a rear elevation view thereof.

FIG. 26 is a front elevation view thereof.

FIG. 27 is a top plan view thereof.

FIG. 28 is a bottom plan view thereof.

FIG. 29 is a rear perspective view of a fifth embodiment of a headphone stand.

FIG. 30 is a left elevation view thereof.

FIG. 31 is a right elevation view thereof.

FIG. 32 is a rear elevation view thereof.

FIG. 33 is a front elevation view thereof.

FIG. 34 is a top plan view thereof.

FIG. 35 is a bottom plan view thereof.

FIG. 36 is a rear perspective view of a sixth embodiment of a headphone stand.

FIG. 37 is a left elevation view thereof.

FIG. 38 is a right elevation view thereof.

FIG. 39 is a rear elevation view thereof.

(Continued)

FIG. 40 is a front elevation view thereof.
FIG. 41 is a top plan view thereof.
FIG. 42 is a bottom plan view thereof.
FIG. 43 is a front perspective view of a ninth embodiment of a headphone stand.
FIG. 44 is a left elevation view thereof.
FIG. 45 is a right elevation view thereof.
FIG. 46 is a rear elevation view thereof.
FIG. 47 is a front elevation view thereof.
FIG. 48 is a top plan view thereof.
FIG. 49 is a bottom plan view thereof.
FIG. 50 is a front perspective view of a tenth embodiment of a headphone stand.
FIG. 51 is a left elevation view thereof.
FIG. 52 is a right elevation view thereof.
FIG. 53 is a rear elevation view thereof.
FIG. 54 is a front elevation view thereof.
FIG. 55 is a top plan view thereof.
FIG. 56 is a bottom plan view thereof.
FIG. 57 is a front perspective view of an eleventh embodiment of a headphone stand.
FIG. 58 is a left elevation view thereof.
FIG. 59 is a right elevation view thereof.
FIG. 60 is a rear elevation view thereof.
FIG. 61 is a front elevation view thereof.
FIG. 62 is a top plan view thereof.
FIG. 63 is a bottom plan view thereof.
FIG. 64 is a front perspective view of a twelfth embodiment of a headphone stand.
FIG. 65 is a left elevation view thereof.
FIG. 66 is a right elevation view thereof.
FIG. 67 is a rear elevation view thereof.
FIG. 68 is a front elevation view thereof.
FIG. 69 is a top plan view thereof.
FIG. 70 is a bottom plan view thereof.
FIG. 71 is a front perspective view of a thirteenth embodiment of a headphone stand.
FIG. 72 is a left elevation view thereof.
FIG. 73 is a right elevation view thereof.
FIG. 74 is a rear elevation view thereof.

FIG. 75 is a front elevation view thereof.
FIG. 76 is a top plan view thereof.
FIG. 77 is a bottom plan view thereof.
FIG. 78 is a front perspective view of a fourteenth embodiment of a headphone stand.
FIG. 79 is a left elevation view thereof.
FIG. 80 is a right elevation view thereof.
FIG. 81 is a rear elevation view thereof.
FIG. 82 is a front elevation view thereof.
FIG. 83 is a top plan view thereof; and,
FIG. 84 is a bottom plan view thereof.
The broken lines showing portions of the headphone stand and environmental elements are for illustrative purposes and form no part of the claimed design.
